UNITED STATES PATENT OFFICE.

HEINRICH KOPPERS, OF ESSEN-ON-THE-RUHR, GERMANY, ASSIGNOR TO H. KOPPERS COMPANY, OF CHICAGO, ILLINOIS, A CORPORATION.

METHOD OF AND MEANS FOR UTILIZING STEAM GENERATED BY QUENCHING COKE.

1,116,297.

Specification of Letters Patent.

Patented Nov. 3, 1914.

Application filed October 28, 1913. Serial No. 797,736.

To all whom it may concern:

Be it known that I, HEINRICH KOPPERS, a citizen of the German Empire, residing at Essen-on-the-Ruhr, in Germany, have invented certain new and useful Improvements in the Method of and Means for Utilizing Steam Generated by Quenching Coke, of which the following is a specification.

- 10 The object of this invention is to provide means for efficiently utilizing the steam generated by the quenching of coke taken from gas-generators. It is in principle highly desirable to utilize this steam in the 15 generator itself, for the reason that some admixtures present in the steam, such as ammonia and sulfur compounds, militate against the use thereof for many other purposes, whereas the return of these admixtures 20 to the generator is in itself useful in that it constitutes a saving of more or less valuable by-products. But the steam is generated at intervals having no direct relation to the rate at which steam is required by the generator, so that in order to utilize the steam 25 some system of storage must be adopted. Steam storage bells or domes, of the gas-holder type, are the most obvious means for this purpose, but even if the periods of 30 steam supply were separated by intervals of only a few minutes the storage chamber would have to be of inconvenient dimensions, and where the intervals are of the duration associated with ordinary gas-generating practice the use of holders for storing the steam itself is quite impracticable 35 for economic reasons. The well-known method of utilizing waste-steam, consisting in introducing the steam into water, to 40 which it gives off heat, and placing the water under vacuum, whereby it is caused to evolve steam, has the advantage of requiring much less storage space, but inasmuch as the vacuum is essential to enable 45 the water, below normal boiling point, to evolve steam, this method is obviously not adapted for utilizing the steam generated by quenching coke and utilizing the steam in the gas generator.
- 50 My invention, however, enables the method of utilizing the steam, by imparting its heat to water, to be effectively applied to the purpose defined. To this end I heat water by means of the steam, and pass the 55 air used in the generator through the hot

water, in a very finely divided state. It is well known that evaporation of water into air or other gas with which it is in intimate contact takes place at temperatures below boiling point, the vapor being generated in 60 accordance with Dalton's law with a partial pressure. It is, accordingly, not essential to the evaporation of water below 100° C. that the water is under vacuum; evaporation also takes place if the water is brought into 65 intimate contact with air not saturated with water vapor. Though this method of utilizing the steam generated by quenching coke is not a direct method, it has very valuable 70 advantages, and the storage of heat in the intervals between the quenching operations is most conveniently effected. Of course a much greater quantity of heat can be stored in a given volume of water than in the same volume of steam. Though the steam derived 75 from the quenching operation undergoes condensation in the water, there is no loss of the by-products referred to, inasmuch as the water becomes enriched there-with and they subsequently pass into the 80 air, their evaporation also taking place at partial pressure. Solid admixtures, on the other hand, are retained by the water and can easily be separated so as to avoid obstruction of the conduits. Another advantage is 85 that the steam of the quenching operation may be generated without pressure, or practically so. If a steam storage chamber were used a certain amount of steam-pressure would of course be required, and this would 90 necessitate the use of steam-tight quenching appliances, which would certainly be inconvenient. In my invention the primary generating of the steam can take place without pressure, the air forced into the generator 95 by the blower serving as a vehicle for the steam generated from the hot water through which it passes.

Apparatus suitable for carrying my invention into effect is diagrammatically illustrated in the accompanying drawing.

In the drawing, 10 designates a bank of retorts, from which the coke is dropped into a truck 11 having perforated walls. The filled truck is run on to a platform 12, which 105 can be lowered into a water tank 13, the quenching pit, the latter being at the bottom of a tower 15 having a door 14 for admission of the truck. The door 14 is closed, and the truck is lowered into the water. 110

The steam generated by the quenching rises in the tower, in which it comes into intimate contact with water trickling down a zig-zag series of baffles. By this means the steam is condensed, giving off its heat to the water. For insuring a very complete exchange of heat a pump 16 forces water from the storage tank 17 to the tower, and the water returns from the latter to the tank. A practically complete absorption of the heat of the steam is thus insured. Hot water from the tank 17 is delivered by a pump 18 to a heat-exchanging tower 19, which is similar in construction to the tower 15, the water flowing down a zig-zag series of baffles 20, and then returning to the tank 17.

The blower 21 furnishing air to the gas generator 23 has its intake pipe joined to the upper part of the tower 19, and sucks air through holes 22 at the bottom of the tower, so that this air is drawn upward through the shower of hot water descending in the tower. In the course of its passage through the tower 19 the air is heated and becomes saturated with water vapor, prior to passing to the gas generator 23.

By regulating the circulation of the water, and accordingly its temperature, the transfer and storage of heat can be regulated at will. The capacity of the tank 17 is such that the water is able to absorb the heat of the intermittent supplies of steam and also to furnish heat to the air at an adequately uniform rate during the intervals between the quenching operations, the fluctuations of temperature of the air supply being no greater than is admissible in practice. To reduce loss of heat by conduction and radiation the tank 17 and the towers 15 and 19 are preferably jacketed or lagged with heat-insulating material.

What I claim is:—

1. The method of utilizing steam generated by successive operations of quenching coke, which consists in imparting the heat of the successive supplies of steam to water and bringing the heated water into intimate contact with a stream of air flowing to a gas generator, whereby evaporation of the water into said stream of air is effected.

2. The method of utilizing steam generated by successive operations of quenching

coke, which consists in imparting the heat of the successive supplies of steam to a stream of water circulating through a storage tank, and bringing water from said storage tank into intimate contact with a stream of air flowing to a gas generator, whereby evaporation of the water into said stream of air is effected. 55 60

3. The method of utilizing steam generated by successive operations of quenching coke, which consists in imparting the heat of the successive supplies of steam to a stream of water circulating through a storage tank 65 and bringing water from said storage tank into intimate contact with a stream of air flowing to a gas generator, whereby evaporation of the water into said stream of air is effected, the rate of circulation of the water 70 being regulated to maintain the variations of temperature within the limits admissible in practice.

4. Apparatus for the purpose set forth comprising in combination a coke-quenching 75 appliance, a water-holder, means for circulating a stream of water whereby water is taken through said water-holder and into contact with steam generated by said quenching appliance, means adapted to propel a stream of air to a gas generator, and means for taking water from said water-holder into contact with air propelled by said propelling means. 80

5. Apparatus for the purpose set forth 85 comprising in combination a coke-quenching appliance, a water-holder, means for circulating a stream of water whereby water is taken through said water-holder into contact with steam generated by said quenching 90 appliance, means adapted to propel a stream of air to a gas generator, and means for circulating a stream of water whereby water is taken through said water-holder and into contact with air propelled by said propelling 95 means.

In witness whereof I have signed this specification in the presence of two witnesses.

HEINRICH KOPPERS.
